UNITED STATES PATENT OFFICE.

WILLIAM P. TALBOT, OF BROOKLYN, NEW YORK.

MANUFACTURE OF WHITE LEAD.

SPECIFICATION forming part of Letters Patent No. 374,716, dated December 13, 1887.

Application filed July 13, 1887. Serial No. 244,196. (No model.)

To all whom it may concern:

Be it known that I, WILLIAM P. TALBOT, of Brooklyn, in the county of Kings and State of New York, have invented a certain new and useful Improvement in the Art of Making White Lead, of which the following is a specification.

The object of my improvement is to provide means for spacing the lead buckles, when piled up in the corroding-pots in the well-known process of making white lead, by a simpler and more acceptable method than has been heretofore employed.

I will first describe in detail a practical mode of carrying my improvement into effect, and then point out the various features of the improvement in the claim.

Reference is to be had to the accompanying drawings, forming a part of this specification, in which similar letters of reference designate corresponding parts in all the figures.

Figure 1 is a vertical section of a corroding-pot, and contains a pile of buckles, illustrating the application of my improvement. Fig. 2 is an enlarged inverted plan view of a lead buckle constructed in accordance with my improvement. Figs. 3 and 4 are cross-sections of the said buckle on the lines *x x* and *y y*, respectively.

The lead buckle A is cast on one side with two parallel blade-like ribs, B, tapering off at either end, arranged on opposite sides of and at equal distances from the diameter, parallel therewith, and extending nearly across the buckle.

In piling a number of lead buckles thus constructed into a corroding-pot, C, with the ribs B downward, as shown in Fig. 1, the shape and arrangement of the ribs cause each buckle to readily find its seat in the pot, and when seated the buckles are properly spaced to admit the corroding-vapor to every portion thereof.

The ribs are, owing to their blade-like form, quickly corroded with the body of the buckle, and thus serve to increase the amount of white lead obtained from each buckle.

Having thus described my invention, I claim as new and desire to secure by Letters Patent—

As an improved article of manufacture, a circular lead buckle cast on one face with blade-like ridges arranged on opposite sides of a diameter of the buckle, but considerably distant from its periphery, as and for the purpose specified.

WILLIAM P. TALBOT.
